[57] CLAIM

The ornamental design for a watch display with an icon, as shown and described.

DESCRIPTION

FIG. 1 is a perspective view of a watch display with an icon showing our new design;

FIG. 2 is a front elevational view thereof, on an enlarged scale, the icon is shown separately for clarity of illustration; and,

FIG. 3 is a front elevational view of the watch display with an icon as disclosed in FIG. 1.

The broken line drawing of a watch in FIGS. 1 and 3 show the environment on which the icon is displayed and forms no part of the claimed design.
